UNITED STATES PATENT OFFICE.

RICHARD D. GALLAGHER, JR., OF FLATBUSH, NEW YORK.

DRAFT GEAR FOR RAILWAY CARS.

1,419,669.

Specification of Letters Patent. Patented June 13, 1922.

Application filed August 11, 1921. Serial No. 491,543.

To all whom it may concern:

Be it known that I, RICHARD D. GALLAGHER, Jr., a citizen of the United States, residing at Flatbush, in the county of Kings and State of New York, have invented certain new and useful Improvements in Draft Gears for Railway Cars; and I do hereby declare the following to be a full, clear, and exact description of the same, reference being had to the accompanying drawings, forming part of this specification.

This invention relates to draft gear and is in the nature of an improvement upon the structure described and shown in my prior Patent No. 1,353,529, dated September 21, 1920. Draft gear of this type are designed to withstand exceedingly heavy draft and buffing strains and involve problems of strain and weight which may to a large extent be ignored in ordinary draft gear when an excess in weight of metal is permissible, but which excess, if employed in proportion in high capacity gear would render the same too weighty and of too great size for practical or desirable practice. It is the object of the present invention, therefore, to provide a high capacity gear having a maximum strength and relatively small weight, the design being especially suitable for use with present permissible standard coupler shanks of reduced cross section without danger of rupturing or upsetting the spring barrel.

In the accompanying drawings,—

Figure 1 is a view looking into the open end of a spring barrel of a gear embodying one form of the present invention.

Fig. 2 is a similar view of a preferred form of barrel.

Figs. 3 and 4 are sectional views in planes indicated by dotted lines 3—3 and 4—4, respectively, of Fig. 1.

Figs. 5 and 6 are sectional views in planes indicated, respectively, by dotted lines 5—5 and 6—6 of Fig. 2.

Fig. 7 is a transverse section in a plane indicated substantially by the dotted line 7—7 of Fig. 5.

The springs, spring plate and frictional elements have been omitted from all of the figures of the drawings, with the exception of Fig. 3, from which last mentioned figure the relation of these parts in the remaining figures of the drawings will be readily understood.

Referring particularly to Figs. 1, 3 and 4, it will be seen that the barrel is a substan-

tially rectangular structure, preferably made of malleable iron or steel and having within it a series of spring cells. These cells are formed by partitions B extending between the side walls A of the barrel and intersecting each other, forming at the intersections relatively heavy points of union which, however, are made somewhat lighter by cored out openings C. In forming the partitions, which latter, it will be understood, are integral with the walls of the barrel, they are made relatively thick and heavy at their inner ends, where they merge into the heavy end wall A' of the barrel, and from that point toward the opposite open end of the barrel they are gradually reduced in thickness in longitudinal lines, and, of course, between adjacent spring cells increase in thickness toward the side or edge walls, owing to the fact that the cells are of generally circular formation.

All of the partitions are formed to extend centrally only to a point about half the distance from the end wall A' to the opposite end of the barrel, as indicated at a in Figs. 3 and 4, but at their edges they extend up along the side and edge walls of the barrel to a point where they merge in the friction box seat or wall forming the mouth of the barrel at C'. This cut out or cut away portion of the transverse partitions in the barrel forms a working space for the spring plate D, center wedge E and side wedges F. For cooperation with these elements, there is mounted in the mouth of the barrel a friction box G, preferably held therein by shear pins lying in recesses in the adjacent faces of the barrel and friction box.

In the end of each cell, adjacent wall A', seats H are formed for the inner ends of the springs, while the outer ends of the springs are held centrally and positioned by co-operation with the spring plate D. The spring plate itself is adapted to move down into the space formed by the cut away portions of the partitions, and to prevent interference with the sides of said partitions, it is preferably recessed or notched opposite each partition side, as in the patent hereinbefore referred to.

The result of the formation of the cells by the upwardly or outwardly tapering partitions is the production of spring cells which taper inwardly or toward the wall A' of the barrel, as will be readily appreciated by reference to Figs. 1 and 2, wherein the

barrel structure is shown in end elevation and in which the inclined walls are clearly indicated at K.

In the structure shown in Figs. 1, 3 and 4, 5 the spring cells are symmetrically arranged in pairs side-by-side and with this arrangement it becomes possible to utilize six heavy springs in the space available for the location of a high capacity draft gear. Under 10 some circumstances, however, it is desirable to make use of but five springs of this character and the structure shown in Figs. 2, 5, 6 and 7 is designed to meet this situation. Referring now to the last mentioned figures 15 of the drawings, it will be seen that there is a central spring cell M and two pairs of spring cells N, N', respectively. In this instance, as in the former instance, the cells are formed to taper inwardly or toward the 20 inner end wall of the barrel, the pairs of cells being formed by outwardly tapering and centrally cut away partitions O, but the center cell is formed in part by said partitions O and in part by the inwardly inclined 25 side walls P of the barrel itself, as shown in Fig. 5. These inwardly inclined central portions of the side walls of the barrel lie opposite those portions of the barrel which are designed to form the bearings for the 30 strap by which the device is connected with the coupler shank, and, hence, it becomes necessary to provide wear or bearing surfaces for said strap. This is accomplished by the formation of webs Q overlying the 35 inner end portions of the side walls P and by offsetting portions of said side walls near the outer end of the barrel as at P'. To strengthen these offset portions and to prevent any possible upsetting or collapse of 40 the barrel under severe strain, the web P² extends longitudinally across the offset portion, as clearly shown in Figs. 5 and 7.

By reference to Figs. 3, 4, 5 and 6, it will be seen that the partitions forming the cells, 45 while of gradually decreasing thickness in all transverse planes parallel with the axis of the barrel, appear in elevation at the outer ends to gradually increase in thickness. This is due to the fact that said partitions 50 are of gradually decreasing width and consequently, when viewed in elevation, the thicker portions are further from the plane of the section or are a less distance from the side walls of the barrel. Attention is 55 called to this appearance because it illustrates the fact that by the distribution of metal in this way the strains imposed on the barrel by a relatively small coupler shank, for example, pressing on the inner 60 end wall of the barrel, will be distributed uniformly to the walls of the barrel without danger of rupture or upsetting the latter when the parts come up solid. The construction is such that the webs have a cross 65 section or bearing value which is approxi-

mately proportioned to the shear lengthwise of the structure and hence the quantity of metal employed may be reduced to a minimum while maintaining the maximum strength and permitting of the use of 70 springs of maximum size and capacity.

I claim:

1. A draft gear comprising a spring barrel closed at one end and open at the other and having a series of inwardly tapering 75 spring cells extending parallel with the line of draft strains, said cells being formed by a plurality of longitudinal partitions having their central portions at the forward ends cut away to form a central working space 80 for the spring plate and their rear ends of gradually increasing cross sectional area and merging into the rear end wall of the barrel, independent springs located in said cells, a spring plate against which the forward ends of the springs abut, a follower and friction elements intermediate the follower and spring plate.

2. A draft gear comprising a spring barrel open at one end and closed at the other 90 and having a series of inwardly tapering spring cells extending parallel with the line of draft strains, said cells being formed by longitudinal partitions integral with and merging into the side and inner end walls 95 of the barrel, said partitions having their central portions at the forward ends cut away on curved lines to gradually reduce their width and form a central working space for the spring plate and of gradually 100 increasing thickness from the outer to the inner end of the barrel, whereby pressure applied to the center of said inner end wall will be distributed uniformly to the side walls of the barrel, independent springs in 105 said cells, a spring plate against which the springs abut, a follower and friction elements intermediate the follower and spring plate.

3. A draft gear comprising a spring barrel of substantially rectangular cross sectional contour to form flat faces for co-operation with the car frame and strap, said barrel being open at one end and closed at the other and with a series of inwardly 115 tapering spring cells formed by transverse partitions integral with the barrel and of gradually increasing thickness from the open to the closed end of the barrel, said partitions being cut away centrally at the forward ends to form a working space for the spring plate, a series of springs in the cells, and a spring plate in the open end of the barrel against which plate the springs abut.

4. A draft gear comprising a spring barrel closed at one end and open at the other, of substantially rectangular cross sectional contour and having a central spring cell and two pairs of oppositely disposed spring cells, the said pairs of cells being formed by par- 125 130 135

- titions in the barrel and the center cell being formed by said partitions and inwardly converging central portions of the side walls of the barrel, said barrel also having flat faces 5 opposite the inwardly converging portions of its wall to form bearing surfaces for the coupler strap, springs in said cells, and a spring plate in the open end of the barrel against which the springs abut.
- 10 5. A draft gear according to claim 4 characterized by having the flat faces for the strap bearings formed at the closed end of the barrel by a web located outside of the inwardly converging walls of the barrel and 15 at the open end of the barrel by outwardly offset portions of said converging walls.
6. A draft gear spring barrel closed at one end and open at the other and having a series of inwardly tapering spring cells extending parallel with the line of draft strains, said cells being formed by a plurality of longitudinal partitions of gradually increasing cross sectional area toward the closed end of the barrel and merging at such end into the end wall of the barrel. 20
7. A draft gear spring barrel closed at one end and open at the other and having a series of inwardly tapering spring cells extending parallel with the line of draft strains, said cells being formed by a plurality of longitudinal partitions of gradually increasing cross sectional area toward the closed end and side walls of the barrel and merging into said end and side walls of the barrel. 25
